NUTATION SYSTEM

John S. Hohl and Ellis T. Davis, Schenectady, N. Y., assignors to General Electric Company, a corporation of New York

Application January 9, 1953, Serial No. 330,492

11 Claims. (Cl. 250—33.65)

This invention relates to an improved nutation system and more particularly to such a system which is adapted for imparting nutation movements of high speed to high frequency electromagnetic radiation antennas of a directional variety such as are used for radar systems, in a scanning operation.

In nutation systems of the type described above, although the radiation antenna which is to be driven is generally a dish-shaped member of light weight conductive material, at the nutation frequencies which are desired, which may fall, for instance, within the range of from eighteen to twenty-four cycles per second, or higher, the accelerations of the various portions of the antenna and nutation system are quite high. Considerable difficulty has thus been encountered in obtaining a smooth operating system which does not have excessive mechanical vibration, excessive bearing wear, and which does not require excessively high power input and an extremely heavy mounting framework.

Accordingly, it is one important object of the present invention to provide an improved nutation system having reduced vibration, requiring less power, and involving less wear on moving parts and permitting a lighter supporting framework.

The term nutation in this patent application is defined as a repeated oscillatory motion of a pivotally mounted body about its pivot. This oscillation or nutation movement may describe a rectilinear path, a circular path or any other non-rectilinear path. In some apparatus requiring directional antenna elements for high frequency electromagnetic radiation, such as radar apparatus, it is very desirable from the standpoint of the design of the remainder of the system to obtain rectilinear nutation. The most convenient and practical driving motors, however, provide for rotational movement. Unfortunately, the mechanisms which must be employed to impart a rectilinear nutation motion of the antenna derived from a circular motion of a drive motor generally increase the vibration and wear difficulties and the allied problems outlined above.

Accordingly, it is a further object of the present invention to provide an improved vibration free nutation system for obtaining rectilinear nutation from a rotational driving motor.

In carrying out the objects of this invention, a nutation system may be employed in which the drive motor is arranged and connected to drive the remainder of the system at a point corresponding to the center of percussion for every phase and direction of operation of the drive motor.

For a more thorough understanding of the invention, reference should be made to the following specification and the accompanying drawings, in which:

Fig. 1 is a perspective drawing of a first preferred embodiment of this invention.

Fig. 2 is a similar perspective drawing of a second preferred embodiment of this invention for providing rectilinear nutation.

Referring more particularly to Fig. 1, there is shown a radiation "dish" 10 which is pivotally mounted by means of integral brackets 11 and 12 to a yoke member 13 which may be in the form of an elliptical hoop for relative rotation about a vertical axis 9. The yoke 13 is in turn mounted by means of pivots 14 and 15 to fixed mountings 16 and 17 for pivotal movement of the yoke 13 and the dish 10 about the horizontal axis 8 determined by the pins 14 and 15. The point of intersection of axes 8 and 9 may be referred to below as the pivot point.

An operating rod 18, which is fastened as an integral part of dish 10, may extend outwardly therefrom for connection to a crank 19 which may be in the form

2

of a disk as shown. The crank includes a counterweight 20 mounted at the end of a counterweight arm 21 for correctly balancing the crank 19 as the dish 10 and yoke 13 are driven through operating rod 18. A suitable motor such as an electrical motor 22 having an output shaft 23 may be employed to support and drive crank 19 to thus drive the nutation system. The motor 22, the crank 19 and associated apparatus may be collectively referred to below as a drive mechanism.

It will be seen that for vertical components of movement of crank 19 and the operating rod 18 the dish 10 and the yoke 13 will both be rotated about the horizontal axis 8 determined by pivots 14 and 15. The inertia of the system for vertical nutation will therefore be the sum of the inertias of the dish 10 and the yoke 13. For horizontal components of movement of operating rod 18, however, only the dish 10 will move about the vertical axis 9 as determined by the pivots at brackets 11 and 12 and the inertia opposing rotation will only be the inertia of the dish 10. Counterweights 24 and 25 are therefore provided at horizontally spaced central positions on dish 10, preferably near the horizontal axis 8 of pins 14 and 15 to increase the inertia of dish 10 about the vertical axis without appreciable increase in inertia about the horizontal axis. The inertia of dish 10 about the vertical axis is thus caused to exactly correspond to the combined inertia of the dish 10 and the yoke 13 about the horizontal axis. It will be obvious that with proper spacing and proper mass of the counterweights 24 and 25, this may be accomplished. The counterweights are mounted by means of arms which extend back towards the crank 19 so that the center of gravity of the entire system is displaced from the pivot point in the direction of crank 19.

The length of the operating rod 18 is chosen so that the point of attachment of crank 19 to the operating rod 18 corresponds to the center of percussion of the double pivoted nutation system including the dish 10 and the yoke 13 about the axes 8 and 9. The center of percussion is defined as the point at which the percussive action of a blow on a pivoted body is the same as if the whole mass of the body were concentrated at the point. By driving the nutation system at its center of percussion, therefore, the reaction forces at the bearings 16 and 17 and 11 and 12 become substantially nil even though the device is driven at frequencies as high as twenty-four cycles per second or more, for instance, in which the rapid accelerations are practically analogous to the percussive action of a blow. With the addition of the counterweights 24 and 25, equalizing the inertia of the system about the vertical and horizontal axes, the centers of percussion of the nutation system for the horizontal axis 8 and for the vertical axis 9 exactly coincide at the point where the operating rod 18 is driven by the crank 19. Therefore there is substantially no change in the load on the motor 22 during the various phases of each cycle of rotation of crank 19. The transition from vertical to horizontal motion is therefore smooth, quiet and vibrationless regardless of the speed or frequency with which the system is driven.

A simple method for calculating and determining the exact center of percussion of a system such as that shown in Fig. 1 and the exact length for operating rod 18 is as follows. The center of percussion is identical to the center of oscillation, and the center of oscillation is defined as a point on a line drawn from the center of gravity of a pivoted body, perpendicular to the pivot axis, whose motion is the same as it would be were the entire mass of the body there concentrated and allowed to vibrate as a pendulum. The distance from the center of oscillation to the pivot axis, which may be called the radius of oscillation, is therefore the same as the length of a hypothetical pendulum pivoted at the same axis of rotation as the body under consideration and having all of its weight concentrated at the center of oscillation (the center of percussion). The simple handbook formula for determining the length of a pendulum is as follows:

$$\text{Length of pendulum } L = \frac{T^2 g}{4\pi^2}$$

Where T is the period of vibration about the axis of suspension in seconds, g is the acceleration due to gravity in feet per second per second, which is a constant known value for a given locality, and π is the geometric constant representing the ratio between the circumference and the diameter of a circle. By employing the above formula, the center of oscillation and the center of percussion, and the length of the operating rod 18 may be determined by pivotally mounting the nutation system including the yoke 13 and the dish 10, swinging the mechanism about either axis under the force of gravity and timing the resulting oscillations. When the oscillation time is known, it may be substituted in the above formula for the T and the required length L of operating rod 18 may therefore be directly determined by computing the formula value. Also, if the oscillations about horizontal axis 8 do not correspond exactly in time with the oscillations about vertical axis 9, the counterweights 24 and 25 may be appropriately altered in mass or position to obtain an exact identity of these times of oscillation so that the centers of percussion for oscillation about these two axes will correspond exactly at a point where the crank 19 may be attached to operating rod 18.

In embodiment of Fig. 1, the operating rod 18 is shown as aligned perpendicular to both axes 8 and 9 and the nutation movement provided by this structure for dish 10 describes a circular pattern. If a rectilinear nutation movement is desired, the end of operating rod 18 can be moved vertically up and down by means of a suitable reciprocating motor rather than the rotational motor 22 which is shown. In such an arrangement the pivots at 11 and 12 could be eliminated as well as the entire yoke 13 and the counterweights 24 and 25. The horizontal pivot pins 14 and 15 could be attached directly to the dish 10 and the center of percussion about the horizontal axis 8 would be the only center of percussion which need be considered. Unfortunately, available reciprocating motors are not as satisfactory and reliable for this purpose as are rotating motors, and it is convenient, therefore, to employ an alternative embodiment of the nutation system of Fig. 1 such as is shown in Fig. 2 in order to obtain rectilinear nutation from rotary motor power.

In the embodiment of Fig. 2, only a rectilinear component of the movement of crank 19 is actually utilized and the horizontal pivot mountings 14 and 15 are connected to the dish 10, rather than to the yoke 13 and conversely the operating rod 18 and the counterweights 24 and 25 are connected to the yoke 13 by suitable supporting arms, rather than to the dish 10. The yoke member 13 is changed from the shape of an oval hoop to a U-shape in order to conveniently accomplish this. In this embodiment, since the dish 10 has no rotation whatsoever about the vertical axis 9, the counterweights 24 and 25 must be selected for the proper mass and 45 position to provide the yoke member 13 plus the counterweights with as great an inertia about the vertical axis 9 as the combined inertia of all of these components 50 plus the dish 10 about the horizontal axis 8. Of course, another objective in the selection of the masses and 55 positions of counterweights 24 and 25 is that the center of percussion should coincide with the point of attachment of operating rod 18 to crank 19 for both the vertical axis 60 rotation system including yoke 13 and counterweights 24 and 25, and the horizontal axis rotation system including all of the above components plus the dish 10. This can be done in a reasonably straightforward manner and this design may be accomplished by the employment of the pendulum principle and formula described at some length above in connection with Fig. 1. The apparatus is swung about axis 8, and the time of 65 oscillation is recorded and the pendulum length or the distance from axis 8 to the center of percussion for that axis is then calculated. Similarly, the system is swung about axis 9 and a similar time observation is made 70 and the center of percussion is then calculated for the system from axis 9. Suitable adjustment of the size and 75 positions of counterweights 24 and 25 may then be made in order to bring these observed centers of percussion together to determine the point at which operating rod 18 and crank 19 should be attached.

The system of Fig. 2 as well as the system of Fig. 1 provides a very smooth operating characteristic since the load on motor 22, connected through crank 19, is again substantially the same during all angles of each rota-

tion. The load represented by the nutation system connected through operating rod 18 to crank 19 is again exactly counterbalanced by crank counterweight 20. The smoothness of operation which is obtainable with this embodiment is considered to be more spectacular since the output motion of radiation dish member 10 represents a rectilinear pattern, while the input from motor 22 is a circular rotation. This embodiment is therefore particularly valuable for the many systems where a rectilinear oscillatory antenna nutation is most desired.

All of the bearings in each of the embodiments are preferably of the anti-friction type, such as those employing rollers, balls, or "needle" bearings, in order to obtain maximum operating ease and a minimum power consumption, and the bearing at the connection between operating rod 18 and crank 19 preferably includes a universal joint or a self-aligning anti-friction bearing. In each of the embodiments, the motor shaft 23 is preferably aligned on an axis which intersects the point at which horizontal axis 8 and vertical axis 9 meet. If properly aligned, an ordinary anti-friction bearing may then be employed at the connection between operating rod 18 and crank 19.

It will be obvious that it is possible to tilt the dish 10 with respect to either or both of the axes 8 and 9 while maintaining the centers of gravity and percussion at the same point by proper adjustment of the mass and positions of counterweights 24 and 25. Such a "tilted" design may be very desirable where other associated apparatus (not shown) must be placed near the dish 10 in positions which would otherwise interfere with the operating rod 18, the motor 22 and associated components.

In the above description of this invention it has been specified that the centers of percussion of the system about the horizontal and vertical axes 8 and 9 should exactly coincide, that the system should be driven exactly at the coincident centers of percussion, that the axes 8 and 9 should intersect at a "pivot point" and therefore should lie in the same plane, and that the pivot axes 8 and 9 should be perpendicular to one another and perpendicular to the operating rod 18. It is true that when all of these conditions exist precisely the maximum and best performance is obtainable. It will be realized, however, that some of the benefits of this invention may be obtained even though slight deviations are made from these ideal design conditions. It should be clearly understood that the greater such deviations may be, the greater the roughness of operation will be and the less the advantages of this invention will be apparent. The design limits beyond which no appreciable advantage of the invention will appear are as follows: (1) where the centers of percussion for rotation about the respective axes 8 and 9 do not coincide, the distance from the pivot point to the further removed center of percussion should not exceed 120% of the distance from the pivot point to the nearer center of percussion; (2) the drive point to which the crank 19 is connected to operating rod 18 should not be displaced from the mean center of percussion (a point midway between the non-coincident centers of percussion) by more than 20% of the distance from the pivot point to the mean center of percussion; (3) the pivot axes 8 and 9 need not intersect and therefore need not lie in the same plane. No limits are stated for the amount of permissible displacement between these axes since the other design limitations which are specified here will determine a practical limit on this displacement; (4) the angle between any pair of the three axes 8 and 9 and the axis of the operating rod 18 should not be decreased below 60 degrees.

The following claims are intended to define the valid scope of this invention over the prior art and to cover all changes and modifications falling within the true spirit and valid scope of the invention.

What we claim as new and desire to secure by Letters Patent of the United States is:

1. A nutation apparatus comprising a member to be nutated, a yoke member pivotally connected thereto for relative rotation about a first axis, one of said members including pivotal supports for rotation about a second axis non-parallel to said first axis, the other of said members including at least one counterbalancing weight for bringing the center of percussion for rotation thereof about said first axis into coincidence with the center of percussion for rotation of the combination of said members about said second axis, said other member also including an

operating member extending to said coincident centers of percussion.

2. A nutation apparatus comprising a member to be nutated, a yoke member pivotally connected thereto for relative rotation about a first axis, said yoke member including pivotal supports for rotation about a second axis non-parallel to said first axis, said nutated member including at least one counterbalancing weight for bringing the center of percussion for rotation thereof about said first axis into coincidence with the center of percussion for rotation of the combination of said members about said second axis, said nutated member also including an operating member extending to said coincident centers of percussion.

3. A nutation apparatus comprising a member to be nutated, a yoke member pivotally connected thereto for relative rotation about a first axis, said nutated member including pivotal supports for rotation about a second axis non-parallel to said first axis, said yoke member including at least one counterbalancing weight for bringing the center of percussion for rotation thereof about said first axis into coincidence with the center of percussion for rotation of the combination of said members about said second axis, said yoke member also including an operating member extending to said coincident centers of percussion.

4. A nutation apparatus comprising a member to be nutated, a yoke member pivotally connected thereto for relative rotation about a first axis, one of said members including pivotal supporting devices for support thereof for rotation about a second axis perpendicular to said first axis, the other of said members including at least two balancing weights for making the center of percussion for rotation thereof about said first axis coincident with the center of percussion for rotation of the combination of said members about said second axis, said other member also including an operating rod extending therefrom away from both of said axes at least as far as to said center of percussion, and a drive mechanism connected to said operating rod at said center of percussion.

5. A nutation apparatus comprising a member to be nutated, a yoke member pivotally connected thereto for relative rotation about a first axis, said yoke member including pivotal supporting devices for support thereof for rotation about a second axis perpendicular to said first axis, said nutated member including at least two balancing weights for making the center of percussion for rotation thereof about said first axis coincident with the center of percussion for rotation of the combination of said members about said second axis, said nutated member also including an operating rod extending therefrom away from both of said axes at least as far as to said center of percussion, and a drive mechanism connected to said operating rod at said center of percussion.

6. A nutation apparatus comprising a member to be nutated, a yoke member pivotally connected thereto for relative rotation about a first axis, said nutated member including pivotal supporting devices for support thereof for rotation about a second axis perpendicular to said first axis, said yoke member including at least two balancing weights for making the center of percussion for rotation thereof about said first axis coincident with the center of percussion for rotation of the combination of said members about said second axis, said yoke member also including an operating rod extending therefrom away from both of said axes at least as far as to said center of percussion, and a drive mechanism connected to said operating rod at said center of percussion.

7. A nutation apparatus comprising a member to be nutated, a yoke member pivotally connected thereto for relative rotation about a first axis, one of said members including pivotal supporting devices for support thereof for rotation about a second axis substantially perpendicular to said first axis, the other of said members including at least two balancing weights for equalizing the moments of inertia and for making the centers of percussion of the combination of said members coincident for movement about either axis, said other member also including an operating rod extending therefrom away from both of said axes at least as far as to said coincident centers of percussion, a drive mechanism comprising a motor having an output shaft, a crank mounted on said output shaft and connected to said operating rod at said center of percussion, said crank including a counterweight positioned

diametrically opposite to the connection of said operating rod for counterbalancing the load connected thereby.

8. A nutation apparatus comprising a member to be nutated, a yoke member pivotally connected thereto for relative rotation about a first axis, said yoke member including pivotal supporting devices for support thereof for rotation about a second axis substantially perpendicular to said first axis, said nutated member including at least two balancing weights for equalizing the moments of inertia and for making the centers of percussion of the combination of said members coincident for movement about either axis, said nutated member also including an operating rod extending therefrom away from both of said axes at least as far as to said coincident centers of percussion, a drive mechanism comprising a motor having an output shaft, a crank mounted on said output shaft and connected to said operating rod at said center of percussion, said crank including a counterweight positioned diametrically opposite to the connection of said operating rod for counterbalancing the load connected thereby.

9. A nutation apparatus comprising a member to be nutated, a yoke member pivotally connected thereto for relative rotation about a first axis, said nutated member including pivotal supporting devices for support thereof for rotation about a second axis substantially perpendicular to said first axis, said yoke member including at least two balancing weights for equalizing the moments of inertia and for making the centers of percussion of the combination of said members coincident for movement about either axis, said yoke member also including an operating rod extending therefrom away from both of said axes at least as far as to said coincident centers of percussion, a drive mechanism comprising a motor having an output shaft, a crank mounted on said output shaft and connected to said operating rod at said center of percussion, said crank including a counterweight positioned diametrically opposite to the connection of said operating rod for counterbalancing the load connected thereby.

10. A non-rectilinear nutation system for a directional high frequency radiation antenna comprising an antenna dish of conductive material, a yoke member, said dish being pivotally mounted on said yoke member for limited rotation about a first axis, fixed pivotal supports for said yoke member for limited rotation thereof about a second axis substantially perpendicular to said first axis, said dish including counterweights horizontally spaced from the central portion thereof for equalizing the moment of inertia of said dish about said first axis with the combined moment of inertia of said dish and said yoke member about said second axis, an operating rod fixed to said dish and extending therefrom, said operating rod being positioned to include a point representing a common center of percussion for said dish for rotation about said first axis and for the combination of said dish and said yoke for rotation about said second axis, a drive mechanism connected to drive said operating rod at said center of percussion, said drive mechanism including a counterbalanced crank at said connection to said operating rod, and a motor having an output shaft connected to rotate said crank.

11. A rectilinear nutation system for a directional high frequency antenna comprising a dish-shaped antenna-member, relatively fixed pivotal support members fastened to said antenna for support thereof for rotation about a first axis, a yoke member pivotally mounted to said dish member for rotation with respect thereto about a second axis perpendicular to said first axis, said yoke member including an operating rod extending outwardly therefrom, said yoke member also including counterweights mounted thereto by means of counterweight arms extending away from said yoke member in directions substantially perpendicular to said second axis to increase the moment of inertia of said yoke about said second axis to correspond to the moment of inertia of the combination of said yoke and said dish member about said first axis, said operating rod being positioned to intersect a point corresponding to the center of percussion of said yoke about said second axis and of said yoke and dish about said first axis, and a drive mechanism comprising a counterweighted crank connected to said operating rod at said center of percussion point, and a motor connected for rotating said crank.
